STABLE OSCILLATORS

James C. Davis, Jr., Carlisle, Mass., assignor to Raytheon Company, a corporation of Delaware

Filed May 7, 1958, Ser. No. 733,643

4 Claims. (Cl. 331—144)

The present invention relates generally to electronic oscillator apparatus, and more particularly to a type of oscillator wherein a resonant tank circuit is coupled to an electronic circuit arrangement in such manner that the pulses of energy necessary to maintain oscillations in the tank circuit are derived from two discharge devices which have a multivibrator or flip-flop action. The multivibrator action is in turn synchronized from the oscillatory wave of the tank circuit, in that the tank provides the energy to trigger the multivibrator into a successive cycle of operation.

A primary object of the present invention is to produce a stable generator of substantially sinusoidal waveform oscillations.

A further object of the invention is to provide a relaxation type oscillator capable of sustaining oscillations by itself, but which is maintained extremely stable in frequency and amplitude by the aid of a frequency controlling tank circuit which is coupled to the oscillator in a novel fashion.

Another object of the present invention is to provide a multi-band variable frequency oscillator having improved amplitude stability with changing frequency within any one band and between one band and another by utilizing cathode follower techniques to minimize loading of the frequency determining tank circuit of the oscillator.

A more specific object of the present invention is to provide a one-shot cathode-coupled multivibrator waveform generator in which an LC tank circuit maintains a stable frequency output which is coupled through a cathode follower stage to obtain an output sine wave shape exceedingly free of distortion.

The above and further objects, advantages and details of the invention will become readily apparent to those skilled in the art upon consideration of the detailed description of a preferred embodiment thereof which follows, reference being made to the single figure of the accompanying drawing.

Two electron discharge devices V-1 and V-2 are provided. The plate of V-1 is connected through a resistor 10 to a source of D.C. energizing potential which may be stabilized to the indicated value of +150 volts by means of a gas discharge voltage regulator tube according to known practice. The plate of V-2 is connected through a resistor 12 to the same potential source. The cathodes of V-1 and V-2 are interconnected and a common cathode resistor 14 connects their junction point to ground.

A feed back condenser 16 is selectively coupled from the plate of V-2 to the grid of V-1 through switch means S-1. An adjustable resistance member R₁, R₂ or R₃ is included in this feed back path for a purpose which will be further explained hereinafter. Grid 18 of V-2 is grounded, so that this right-hand tube of the multivibrator pair may be considered in some respects to

2

function as a "grounded-grid" amplifier having a cathode input and a plate output.

A resonant circuit consisting of a variable condenser C and a selected inductance L₁, L₂ or L₃ is connected in the grid return path between the grid of V-1 and ground. Switch means S-2 effects the selection of an individual inductance to cover a particular band of frequencies. The motion of switch means S-2 is preferably ganged with that of S-1 as indicated by the dotted line in the drawing.

A third discharge device, V-3, is driven from the resonant circuit to provide the output signal. The plate of V-3 is connected through a resistor 20 to the D.C. potential source, and the cathode is connected to ground through serially connected resistors 22 and 24. The input grid of V-3 is returned to the junction of resistors 22 and 24 through resistor 26. Input condenser 28 couples the resonant circuit to the grid of V-3. It is to be noted that condenser 28 should be of small magnitude to provide loose coupling from the resonant circuit to the output stage of V-3 so as to minimize damping or pulling of the oscillation generator output. At the same time, grid return resistor 26 should be sufficiently large in magnitude so that the combination of condenser 28 and resistor 26 does not act to differentiate the input waveform.

Discharge device V-3 is operated as a cathode follower with the output waveform taken across the cathode load resistors through a coupling condenser 30 connected to a first output terminal 32. A second output terminal 34 is connected to the cathode follower output by way of a resistor 36. This second output terminal is optionally included so as to provide an additional output wave having a characteristic similar to that obtainable from terminal 32 for operation of a counting device.

In operation of this invention resistance element 14 provides the bias for electron discharge devices V-1 and V-2. When oscillation occurs in this invention the oscillatory signal builds up in amplitude until the negative grid swing of the oscillatory signal cuts off discharge device V-1. The cathode of discharge device V-1 is held positive by the current flowing in discharge device V-2 and the resistance element 14.

When discharge device V-1 is substantially cut off as described above the gain of discharge device V-1 approaches zero and this limits the amplitude of the oscillations. Due to discharge device V-1 being cut off by the negative peak, the wave form impressed upon resistance element 14 will be a sinusoid with the negative peak flattened or cut off. Inasmuch as discharge devices V-1 and V-2 are broad band amplifiers without reactance in the range of frequencies employed in this invention, the cutoff of discharge device V-1 and therefore the amplitude of the oscillations will be independent of the frequency.

The function of resistance elements R-1, R-2 or R-3 is to selectively decouple the tank circuit from the plate of discharge device V-2, thereby minimizing the effects of parameter changes in discharge device V-2 on the tank circuit comprising the inductance and capacitance.

Utilizing the well-known theory of cathode followers, that no grid current is drawn by discharge device V-1, the effect of parameter changes inside discharge device V-1 on the tank circuit is also minimized. Because of this minimizing effect of the parameter changes the frequency of this oscillator is a function only of the tank circuit inductance and capacitance. The stability of the oscillator is therefore effectively a function of the stability of the components L and C.

The wave shape in the tank circuit is a pure sine wave. The bias of discharge device V-3 is such that V-3 oper-

ates linearly over the entire wave shape and the output of V-3 is a pure sine wave. As noted above, the well-known theory of cathode followers indicates that the effects of V-3 on the tank circuit will also be minimal, as were the effects of V-1.

Various modifications of the embodiment shown in the drawing may be made without affecting the scope of the present invention, as will occur to those skilled in the art. For example, the discharge devices V-1 and V-2 may be combined in a single envelope, and device V-3 which is illustrated as being a triode-connected tetrode may be any other multi-grid tube operated as a triode, or may be a triode if desired. Alternatively, the vacuum tube discharge devices may be replaced with their transistor equivalents according to known theories of duality. Also, in certain applications where the oscillation frequency range permits, the LC resonant circuit may be replaced by equivalent means such as piezo crystal or cavity resonator.

Accordingly, the foregoing description is to be taken by way of illustration only, and not as limiting the practice of the invention, which should be interpreted according to the scope of the appended claims.

I claim:

1. A periodic waveform generator including a pair of electron discharge devices each having a grid, a cathode and an anode, a source of anode potential having one terminal connected to said anodes and a second terminal connected to ground, a common cathode bias resistor to limit grid current flow and to further provide a first feedback path having one terminal connected to said cathodes and a second terminal connected to ground, a capacitor and a resistor connected in series interconnecting the anode of one electron discharge device and the grid of the other discharge device to provide a second feedback path, means connecting the grid of said one electron discharge device directly to ground, and a resonant frequency determining circuit connecting the grid of said other electron discharge device to ground.

2. A periodic waveform generator including a pair of electron discharge devices each having a grid, a cathode and an anode, a source of anode potential having one terminal connected to said anodes and a second terminal connected to ground, a common cathode bias resistor to limit current flow and to further provide a first feedback path having one terminal connected to said cathodes and a second terminal connected to ground, a capacitor and a resistor connected in series interconnecting the anode of one electron discharge device and the grid of the other discharge device to provide a second feedback path, means connecting the grid of said one electron discharge device directly to ground, a resonant frequency determining circuit connecting the grid of said other electron discharge device to ground, and output wave shaping means connected to the grid of said other electron discharge device.

3. A waveform generator comprising in combination two electron discharge devices, said devices each having a cathode, an anode and at least one grid, a direct cur-

rent source, individual impedance means connected between the anode of each device and the positive terminal of said source, an impedance common to said cathodes connected between said cathodes and the negative terminal of said source, circuit means including a resistor in

5 series with a condenser connected between the anode of one of said devices and a grid of the other device, a direct connection between a grid of said one device and the negative terminal of said source, a resonant circuit connected between a grid of said other device and the negative terminal of said source, and output wave shaping means loosely coupled to the grid of said other device.

4. A frequency stable sine wave generator including an electron discharge network comprising a first electron discharge device having cathode, grid and anode electrodes, a second electron discharge device having cathode, grid and anode electrodes, resistors connected to the anode electrodes of said devices, a capacitor and resistor connected in series intercoupling the grid of said first device and the anode of said second device, a direct connection between the grid of said second device and ground, means to connect the positive pole of a source of direct current potential to said anode resistors and to connect the negative pole of said source to ground, a connection between the cathodes of both of said devices, a coupling resistor connected between said cathode connection and ground, said coupling resistor having a value normally at which said second device is rendered conducting and said first device is blocked due to current flow of said conducting second device, a resonant circuit connected between the grid electrode of said first device and ground to periodically render the first device conducting and block said second device at the resonant frequency of said resonant circuit to sustain sine wave oscillations, a third electron discharge device having cathode, grid and anode electrodes, a resistor connected between the anode of said third device and the positive pole of said source of direct current, a coupling capacitor connected from the grid of said first device to the grid of said third device for providing loose coupling from the resonant circuit to said third device, a cathode resistor connected from the cathode of said third device to ground, and a grid resistor connected from the grid of said third device to intermediate the ends of said cathode resistor, said grid resistor having a value so that the combination of said grid resistor and said coupling capacitor does not act to differentiate an input signal to the grid of said third device.
